UNITED STATES PATENT OFFICE.

DAVID DUBENDORF, OF MIDDLETOWN, PENNSYLVANIA.

HOSE-CLAMP APPLIER.

No. 883,099.

Specification of Letters Patent.

Patented March 24, 1908.

Application filed July 23, 1907. Serial No. 385,160.

To all whom it may concern:

Be it known that I, DAVID DUBENDORF, a citizen of the United States, residing at Middletown, in the county of Dauphin and State 5 of Pennsylvania, have invented new and useful Improvements in Hose - Clamp Appliers, of which the following is a specification.

This invention relates to hose clamp appliers, and particularly to a tool for applying wire hose clamps of the U-type, in which the ends of the wire of the clamp are interlocked with the bight portion thereof and turned back to prevent disconnection.

15 The object of the invention is to provide a tool of this character by which such clamps may be quickly, conveniently and tightly applied.

The invention consists of the features of 20 construction, combination and arrangement of parts hereinafter fully described and claimed, reference being had to the accompanying drawing, in which:—

Figure 1 is a side view of the tool, illustrating in dotted line the operative movement of the strainer-bar. Fig. 2 is a front elevation of the tool. Fig. 3 is a top plan view thereof. Fig. 4 is a detail view of the block carrying the stationary clamps. Fig. 5 is a side view 30 of the hose clamped to a pipe or coupling by the tie. Fig. 6 is a cross sectional view of the same.

The tool is employed for applying wire clamps of the construction shown in Figs. 5 35 and 6 to hose pipes for the purpose of fastening the same to couplings or fluid conductors and as therein shown it will be seen that the clamp 1 comprises a ring formed from a single piece of wire bent primarily into U-form, 40 the ends 2 of the wire being passed through the space between the arms of the loop at the closed end thereof and interlocked with the bight portion 3 by bending them back to form locking hooks engaging said bight portion. Clamps of this type may be purchased 45 in the open market in the form disclosed ready for application to the hose, it being understood that in the operation of the present tool a clamp which loosely fits the hose is 50 employed and is drawn or strained into clamping engagement therewith.

The tool comprises a head composed of a 55 pair of parallel plates 4 having straight front edges and provided at their upper forward ends with extensions 5, the front portions of the plate being held in spaced relation by dis-

tance blocks or pieces 6 and 7. The blocks or pieces 6 may be integral with the plates and are arranged to act in conjunction with the blocks 7 to provide a vertical guide-way 60 for a sliding strainer-bar 8 formed at its upper end with a transverse groove 9 and a lip or projection 10. The rear portions of the plates are held spaced by the oblique arm 11 of a straining lever 12 pivotally mounted on 65 a pin 13 passing through the plates, the forward end of the arm 11 being provided with a rounded projection or knuckle 14 loosely fitting within a recess 15 formed by a pair of spaced lugs on the rear of the bar 8, by which 70 said lever is pivotally connected with the bar to slide the same up and down.

A clamping lever 16 is arranged at the front of the head and provided with a central rearwardly extending lug 17 pivotally mounted in any suitable manner between the plates to adapt said lever to have a rocking movement. The lower arm 18 of the lever is pivotally connected by links 19 arranged on opposite sides of the head with the arms of the 80 bifurcated portion of a combined operating lever and handle 19, the bifurcated portion of which is pivotally connected with the lower rear portion of the head by a pin 20.

The upper arm 21 of the lever 18 is formed 85 with a pair of inwardly extending rigid clamping jaws 22 beveled on their upper and lower surfaces to points at their free edges and provided in their upper faces with downwardly and inwardly extending grooves 23. 90 These jaws are adapted to project between opposite sets or pairs of upper and lower relatively stationary clamping jaws 24 and 25 formed upon and extending laterally from the distance block 7, which is preferably 95 made of some durable metal and is fastened between the upper front corner portions of the plates 4 in any preferred manner. Between these sets of jaws the block 7 is formed to provide a beveled boss 26 adapted 100 to be received in the space between the jaws 22 of the lever 16 when the latter is in clamping position. The lower jaws 25 are provided in their front edges with grooves 27 and are arranged in advance of the front edges of 105 the jaws 24, which are beveled to bending edges, as indicated at 28. The strainer-bar 8 and remaining parts of the tool normally lie in the positions shown in Fig. 1, and a latch device 29 is provided to lock the strainer-bar 110 normally in its lowered position. This latch device is pivotally mounted upon one

of the plates 4 and is provided at its inner end with a locking pin 30 movable through an opening in said plate to engage a notch or recess 31 in the rear edge of the bar. The outer 5 end of the lever forms a finger-piece 32 between which and the adjacent side of the lever 16 is arranged a spring 33 operating to normally hold said locking device in locking position.

10 In operation, a clamp 1 of the construction described and of a size to loosely fit upon the hose is placed thereon after the hose has been applied to the pipe or coupling. The tool and hose are then so relatively positioned 15 that the hose extends transversely above the block 7 and lever 16, the hooked ends 2 of the tie 1 being passed downwardly between the sets of jaws 22, 24 and 25 and passed under the jaws 25 and arranged to lie in the re- 20 cesses 27 thereof, and the bight portion 3 of the tie finally fitted into engagement with the lip 10 of the straining lever 8, so that it will rest into the groove 9. The lever 12 may then be employed as a stationary handle in 25 conjunction with the lever 19 as a movable handle, whereby the latter may be swung upward to rock the lever 16 to swing its jaws 22 inwardly, which jaws will thereby pass into the spaces between the sets of jaws 24 and 25 30 and crimp the hooks 2 therein, which hooks will extend through the grooves 23 and 27, whereby the locking ends of the wire clamp will be tightly held from movement and arranged to lie at the proper angle. The clamps 35 being held in such position by the lever 19, which may be now employed as a stationary handle, the latch 29 is released, and the lever 12 as a movable handle pressed downward to slide the straining-bar 8 upward, by which 40 the bight portion 3 of the tie held in engagement with the lip 10 will be strained or drawn upon to contract the tie and draw it into close clamping engagement with the hose, which will thereby be firmly fastened to the 45 pipe or coupling, after which the bar 8 is retracted by the lever 12 and the jaws 22 retracted by the lever 19 to release the tie from the tool. In the straining operation above described, it will be understood that the 50 operation of moving the bight 3 upwardly while the ends 2 are being held results in the arms of the wire clamp being moved through the bight portion to draw the clamp closely around the hose without liability of im- 55 pairing the locking efficiency of the hooked ends 2 which are held in their normal locking position by the action of the clamps. After the application of the tie or clamp the hooked ends 2, which are lengthened by the 60 straining action, may be cut off as short as desired to make them lie as closely as possible to the hose.

From the foregoing description, taken in connection with the accompanying drawings, 65 the construction, mode of operation and ad-

vantage of my improved wiring device will be readily understood, and it will be seen that the invention provides a simple and effective device, whereby a clamp or tie of the character described may be quickly, conveniently and tightly applied. 70

Having thus described the invention, what I claim as new and desire to secure by Letters Patent is:—

1. A tool for applying annular wire clamps 75 of the type described to hose comprising a head carrying stationary clamps, a pivoted clamp to coöperate therewith, a pivoted lever for operating the pivoted clamp, a sliding strainer bar, and a pivoted operating lever 80 therefor pivotally connected with said bar.

2. A tool for applying annular wire clamps of the type described to hose comprising a head carrying stationary clamps, a pivoted clamp to coöperate therewith, a pivoted 85 lever for operating the pivoted clamp, a sliding strainer bar, locking means for normally holding said bar inoperative, and a pivoted lever for operating the bar.

3. A tool for applying annular wire clamps 90 of the type described to hose comprising a head carrying pairs of superposed stationary clamping jaws, the lower clamping jaws being formed in their forward edges with grooves and projecting in advance of the 95 upper clamping jaws, the latter being provided with bending edges, a clamping lever pivotally mounted upon the forward portion of the head and having a pair of pointed clamping jaws to move between the pairs of 100 stationary jaws, a strainer bar arranged to slide upon the head in rear of said stationary clamping jaws, a pivoted lever for operating the clamping lever, a locking means for holding the bar inoperative, and a pivoted 105 lever for sliding said bar.

4. A tool for applying annular wire clamps of the type described to hose comprising a head carrying stationary clamping jaws, a pivoted clamping lever carrying coöoperating 110 clamping jaws, an operating lever therefor fulcrumed on the head, a link connection between said lever and the clamping lever, a strainer bar slidably mounted on the head, and an operating lever therefor fulcrumed on 115 the head and pivotally connected to said bar.

5. A tool for applying annular U-shaped ties to hose, comprising a head, stationary clamps upon the head, a movable clamp to operate therewith to hold the ends of the tie, 120 means for operating said movable clamp, a sliding strainer bar to engage the bight of the tie and draw thereon to contract the tie about the hose, locking means for normally holding said bar inoperative, and means for 125 actuating said bar.

6. A device for applying annular U-shaped wire ties to hose, comprising a head, stationary clamps upon the upper forward portion of the head, a pivoted clamp to coöperate 130

therewith to hold the ends of the tie, an operating lever pivoted upon the rear portion of the head, a pivotal connection between said lever and the pivoted clamp, a 5 sliding strainer bar arranged for movement in rear of the plane of the stationary clamps, said bar having at its upper end a recess and a lip to receive and engage the bight of the hose, and a lever fulcrumed on the head for

sliding said bar to contract the tie about the 10 hose.

In testimony whereof, I affix my signature in presence of two witnesses.

DAVID DUBENDORF.
